UNITED STATES PATENT OFFICE.

GEORGE H. HIGGINS, OF CORTLAND, NEW YORK, ASSIGNOR TO CORTLAND CARRIAGE GOODS CO., OF CORTLAND, NEW YORK, A CORPORATION OF NEW YORK.

ONE-MAN TOP.

1,217,120.

Specification of Letters Patent. Patented Feb. 20, 1917.

Application filed February 14, 1916. Serial No. 78,192.

To all whom it may concern:

Be it known that I, GEORGE H. HIGGINS, a citizen of the United States of America, and resident of Cortland, in the county of 5 Cortland, in the State of New York, have invented new and useful Improvements in One-Man Tops, of which the following, taken in connection with the accompanying drawings, is a full, clear, and exact description.

10 This invention relates to certain improvements in folding tops for touring cars, motor boats and other vehicles, commonly known as "one-man extension tops", in that 15 it may be extended, folded or "crashed" by a single individual without assistance, and it is an improvement upon the structure disclosed in my co-pending application, Serial No. 858,032, filed August 22, 1914.

20 The main object of the invention is to enable such a top to be easily and quickly extended or folded by a single operator and without excessively elevating or depressing any parts of the same during the operation.

25 Specifically the invention provides means for automatically moving the forward bow sockets and bows to extended position upon the movement of the main arm or main bow to its extended position.

30 Other objects and advantages will appear from the following description, taken in connection with the accompanying drawings, in which—

35 Figure 1 is a side elevation of an upper portion of an automobile body showing one specific application of my improved foldable top, the dotted lines at the left indicating the folded position, while the dotted lines at the right indicate a semi-folded or semi-40 extended position.

Fig. 2 is a cross section on line 2—2, Fig. 1.

45 As previously intimated, this folding top is adapted to be used in connection with touring cars and similar vehicles requiring a top of considerable length, and may embody any suitable or desirable number of bow sockets and bows, the specific illustration herein showing four bows, a rear bow 50 —1—, a rear auxiliary bow —2—, a front auxiliary bow —3—, and a front bow —4— carried by analogously identified bow receiving arms or bow sockets —5—, —6—, —7— and —8—, respectively, the bows 55 adapted to support and tension a suitable

flexible top or covering —a— having its rear end fastened in the usual manner to the rear end of the body of a vehicle, as —A—.

The main arm or bow socket —9— may be made hollow so that it may or may not 60 carry and support a bow, dependent upon the number of bows required. This main arm —9— is pivotally supported from the body at —10—, and the rear bow socket —5— is pivotally carried from the arm 65 or bow socket —9— at a point slightly above and adjacent the pivot —10—.

The front bow socket —8— is constructed in the form of toggle sections —11— and —11'— pivoted to the intermediate portion 70 of the arm —9— at —12—, and the toggle joint —13— between the sections —11— and —11'— is positioned above the plane of the arms and above a line connecting the pivot —12— with the end of the bow socket 75 —8—, thereby automatically retaining the parts in locked position against downward displacement under vibration of the machine, or other accidental causes.

The bow socket —6— is pivotally attached to the rear of the arm —9— at any desired point thereon, and preferably in extended position of the top, extends rearwardly therefrom.

80 The bow socket —7— is pivotally carried by the toggle section —11— and, in extended position of the top extends upwardly and forwardly therefrom.

85 The bow socket —7— is connected to the toggle section —11'— by a link or tie-piece 90 —14— pivoted at —15— to the bow socket —7— and at —16— to the toggle section —11'—. The arm —9— is extended upwardly beyond the pivot —12— and is pivotally connected at a point above the pivot 95 —12— to a link or tie-piece —17—, one end of which link or tie-piece is connected to the bow socket —7— at a point between the pivot —15— and the point of connection of said bow socket to the toggle section 100 —11—.

105 The links —14— and —17— carry the bow sockets —7— and —8— in proper relative position, relieving the flexible top from excessive strains by limiting the forward swinging movement of said sockets in relation to the main arm —9— and by tending to prevent downward movement of the toggle joint —13—.

110 For the purpose of automatically throw-

ing forward and extending the bow sockets —7— and —8— when the arm or bow —9— is raised to extend the top and for collapsing the said parts when the bow —9— is moved 5 rearwardly, the link —17— is extended rearwardly from its pivot —18— upon the arm —9— to form a lever arm or crank —19— pivotally connected at —20— to a link —21—, which link is in turn pivoted to the 10 bow socket —6— at the point —22—.

The crank —19— and link —21— are so shaped, arranged and proportioned as to be in close juxtaposition to the bow sockets in collapsed position.

15 It will be readily apparent that when the top has been moved, as shown in dotted lines at the right of Fig. 1, toward its extended position that any farther forward movement of the arm —9— will cause a 20 rocking movement rearwardly of the bow socket —6— and its bow —2—, whereby the link —21— is moved downwardly to rock the crank arm —19— about the pivot —18—, whereby the link —17— is raised 25 to raise the bow socket —7— and its bow —3— and move the bow socket —8— toward complete extended position.

By raising the main arm —9— to extended position of the top, the bow sockets 30 and their bows are all automatically moved to extended position of the top without the necessity of the operator releasing the arm —9— or moving from the position taken in raising the arm —9— to its extended position.

The operation of extending the top is automatically completed by the initial movement of any forward bow socket to its position of complete extension.

40 Although I have shown and described one specific construction and method of operation, I do not desire to limit myself to the same, as many changes may be made in the details of form, arrangement and operation without departing from the spirit 45 of this invention as set forth in the appended claims, the basis feature of which resides in the automatic movement of the forward bows to their extended position by 50 merely moving, preferably a single bow socket or arm to the position which it necessarily assumes when the top is extended.

What I claim is:

1. In a folding top for vehicles, a main 55 arm, a toggle socket having its rear section hinged to said main arm, a front auxiliary bow socket hinged to the rear section of the

toggle socket, a rear auxiliary bow hinged to the main arm, a link connecting the front auxiliary bow socket to the front section of the toggle, a tie-piece connecting the main arm to the front auxiliary bow socket, said tie-piece provided with a crank arm, and a link connecting said crank arm to the rear auxiliary bow socket. 60

2. In a folding top for vehicles, main arms, toggle sockets hinged to the main arms, front auxiliary bow sockets hinged to the rear sections of the toggle sockets, tie-pieces connecting the upper ends of the main arms to points on the front auxiliary bow sockets below their centers, and links connecting the front toggle sections to points on the front auxiliary bow sockets above their centers, a rear auxiliary bow 70 socket, said tie-pieces provided with projecting lever arms, and links connecting said lever arms to said rear auxiliary bow sockets. 75

3. In a folding top for vehicles, main arms, toggle sockets hinged to the main arms, front auxiliary bow sockets hinged to the rear sections of the toggle sockets, tie-pieces connecting the upper ends of the main arms to points on the front auxiliary bow sockets below their centers and links connecting the front toggle sections to points on the front auxiliary bow sockets above their centers, a rear auxiliary bow socket, and means connected to the tie pieces 85 and actuated by moving the main arm to extended position for rocking said tie-pieces about their pivots on the main arms to move the toggle bow sockets and the front auxiliary bow sockets toward extended position. 90

4. In a folding top for vehicles, a main arm, a toggle socket having its rear section hinged to said main arm intermediate the length of said arm, a front auxiliary bow socket hinged to the rear section of the toggle socket, a rear auxiliary bow socket, a tie-piece pivotally connecting the front auxiliary bow socket and said main arm above the pivot of the rear section of the toggle socket, said tie-piece provided with a crank 100 arm, and a link connecting said crank arm to the rear auxiliary bow socket. 105

In witness whereof I have hereunto set my hand this 10th day of February, 1916.

GEORGE H. HIGGINS.
